UNITED STATES PATENT OFFICE.

ERVIN A. GOERTZ AND WALTER H. KROENKE, OF FARIBAULT, MINNESOTA.

HEADLIGHT REFLECTOR.

Application filed August 22, 1923. Serial No. 658,711.

To all whom it may concern:

Be it known that we, ERVIN A. GOERTZ and WALTER H. KROENKE, citizens of the United States, residing at Faribault, in the county of Rice and State of Minnesota, have invented certain new and useful Improvements in Headlight Reflectors; and we do hereby declare the following to be a full, clear, and exact description of the invention, such as will enable others skilled in the art to which it appertains to make and use the same.

Our invention relates to headlight reflectors such as used in connection with automobiles and similar vehicles for lighting the road ahead of the machine. The object of the invention is the provision of a reflector which will throw all or substantially all of the light onto the road for the purpose of illuminating the road, thereby, at the same time, eliminating upwardly projecting rays such as would produce blinding effects in the eyes of persons in approaching machines.

In carrying out the invention, we provide a reflector that will throw all of the reflected rays onto the road ahead of the machine and will spread the light beam laterally, so as to give full road illumination and give illumination in turning corners or curves. Some of the direct rays will have a slight upward projection, but such upwardly projected rays will produce only a mild overhead illumination such as desirable to enable the driver to see overhanging objects, such as tree limbs, and will not produce a blinding glare in the eyes of persons in approaching machines.

In the accompanying drawings, we have illustrated a reflector that illustrates our invention in what is considered its preferred commercial form.

Referring to the drawings:

Fig. 1 is a front elevation of the improved reflector;

Fig. 2 is a vertical axial section taken through the reflector on the line 2—2 of Fig. 1; and

Fig. 3 is a horizontal section taken on the line 3—3 of Fig. 1.

By reference to Fig. 1, it will be noted that the reflector 4 is circular at its rim, which feature is highly desirable, first because an ordinary circular lens or glass cover plate may be employed in connection therewith, and second because the reflector

in front elevation will have much the appearance of an ordinary reflector.

The reflector is indicated as an entirety by the numeral 4 and its axis is substantially on the line *a—a*. Projected through the back of the reflector on the axis thereof is a light bulb socket 5 that holds a light bulb 6 in position within the reflector with its center or hot spot of its filament on the axis *a—a* substantially at *a'*. This reflector has radial sections that vary greatly in their lines or curves from the upper vertical radial plane to the lower vertical radial plane. For example, in its vertical axial section, the reflector, from the point *b* to point *c*, is or may be a true curve struck from the point *a'*; from the point *c* to point *d*, said reflector is approximately horizontally extended on an approximately straight line; from the point *b* to point *e*, the radial section of said reflector is a hyperbolic curve or approximately such curve. In horizontal radial sections on the line 3—3, (see Fig. 3), the reflector has elliptical or substantially elliptical curves from the axial point *b* to the rim points *f*. The oblique radial sections of the reflector will vary progressively from the one to the other of the curves above described. In that portion of the reflector that is above the plane of the axis *a—a*, the elliptical or approximately elliptical curves *b—f* may be blended into the curve *b—c—d* in any suitable way but preferably as gradually as possible. In that portion of the reflector that is below the plane of the axis *a—a*, the radial sections are preferably all conics; and progressing from the conic curves *b—f*, which have an eccentricity less than one, into the hyperbolic curves *b—e*, which have an eccentricity greater than one, the variation in curve will produce in the reflector an oblique radial section having a parabolic curve or conic with an eccentricity of one, approximately at the oblique radial sections that are at an angle of 45° to the horizontal plane of the axis *a—a*.

In Figs. 2 and 3, the broken lines indicate certain of the reflected rays, and in Fig. 2, the dotted line indicates the uppermost of the direct rays.

By reference first to Fig. 2, it will be noted that the light bulb is located close to the approximately horizontal hood or top portion of the reflector, so that the most intense of the reflected rays will strike the top or upper

105

110

portion of the reflector and be projected downward onto the road ahead of the machine. It will also be noted that the reflected rays that strike the lower portion of 5 the reflector will be projected downward onto the road, so that all of the reflected rays reach the road and only part of the direct rays are projected above the horizontal plane of the axis a .

10 By reference to Fig. 3, it will be noted that the reflected rays, on striking the elliptical curves $b-f$, are crosswise projected in front of the reflector and spread out on opposite sides of the reflector so as to give the 15 desired wide road illumination. Only a comparatively small part of the reflected rays will, however, be thus widely spread on the road, for most of the rays and the most intense rays will be projected onto the 20 road within a comparatively small lateral space so as to give the most intense illumination on the road to be traveled by the machine.

The above described arrangement gives 25 substantially an ideal distribution of the light. It gives the desired mild overhead illumination, the desired mild illumination at the sides of the road, and the more intense illumination on the road proper that is 30 to be traveled by the machine. Thus, no

light is actually wasted and the best possible illumination is produced and blinding glare is eliminated. This reflector will produce a light beam that will meet the requirements of the illumination-regulating ordinances or 35 laws of the various different states and cities. The reflector may be stamped to form at no greater cost than that of an ordinary reflector and it is adapted to be used with a plain or simple clear glass lens or cover plate. 40

What we claim is:

A head light reflector set on a horizontal axis and combined with a light bulb, the back of the reflector above the horizontal axis of the light bulb being concentric with 45 the focal point of the light bulb and terminating at the vertical axis thereof, the top of the reflector being parallel to the horizontal axis of the light bulb and extending tangentially from said back and the lower portion of the reflector below the horizontal axis of the light bulb following the line of hyperbolic curve, said reflector in the horizontal plane of its axis follows an elliptical curve 50 and the rim of said reflector is round. 55

In testimony whereof we affix our signatures.

ERVIN A. GOERTZ.
WALTER H. KROENKE.
